(57) **CLAIM**

The ornamental design for a vehicle antenna, as shown and described.

DESCRIPTION

FIG. 1 is a perspective top left view of a vehicle antenna according to the present invention;

FIG. 2 is a front elevational view thereof;

FIG. 3 is a rear elevational view thereof;

FIG. 4 is a left side elevational view thereof, the right side elevation view being a mirror image thereof;

FIG. 5 is a top plan view thereof; and,

FIG. 6 is a left side elevational view showing the vehicle antenna in use, mounted on a roof of a vehicle.

The right side elevational view of the vehicle antenna is a mirror image of the left side elevational view thereof. The bottom of the vehicle antenna is flat and planar.

The broken lines shown in FIG. 6 illustrate environmental subject matter only, such as a roof of a vehicle, and form no part of the claimed design.
